GAME DEVICE

Lewis La Voice, Springfield, Mass., assignor of
one-half to Earl Rowe, Springfield, Mass.

Application September 26, 1935, Serial No. 42,295

1 Claim. (Cl. 273—106)

This invention relates to improvements in game devices and is directed more particularly to the provision of a novel device for use in the well-known game of pitching shoes.

It is a principal object of the invention to provide a device which is novelly constructed and arranged so that when it is thrown at a stake or the like so as to come into contact therewith, it is more likely to come to rest in the desired position around the stake. That is to say, the pitching shoe of this invention is formed in a certain way which makes it more desirable for its intended purpose in the playing of the game.

It is another object of the invention to provide a pitching shoe of the class described which is constructed in such a way that the sliding of the device along the ground is facilitated if the same should happen to strike the ground prior to its reaching the stake.

A still further object of the invention is to provide a device which is distinctive in form and has novel gripping means which renders the device easier to use. Not only is the shoe of this invention simple in form so as to be economical to manufacture but it tends to contribute much to the pleasure of the game.

Various other objects and advantages will become more apparent after a reading of the following description and reference will be had to the accompanying drawing wherein:

Fig. 1 is a plan view of the device of the invention;

Fig. 2 is a side elevational view of the device shown in Fig. 1;

Fig. 3 is a sectional view on the line 3—3 of Fig. 1;

Fig. 4 is a sectional view on the line 4—4 of Fig. 1; and

Fig. 5 is a sectional elevational view on the line 5—5 of Fig. 1.

Referring now to the drawing more in detail, the invention will be fully described.

In the drawing, there is shown a device 2 which is generally U-shaped and this may be made of any relatively rigid material, such as cast iron or the like. It preferably is made in such a way that it consists of a single or integral piece of material.

The device 2 has what may be called a main body portion 4 which is preferably curved in the form of a semi-circle as shown and there are side arm portions 6 extending forwardly in spaced relation from the opposite ends of the semi-circle. The body 4 and arms 6 have gen-

erally flat surfaces in substantially the same plane.

On one side of the central part of the body part 4 there is provided a raised calk-like portion 8. The forward face 10 of this portion 8 slopes downwardly as shown, while there are beveled parts 12 at opposite sides of the part 8.

It will be seen that the rear side of the part 8 is relatively wider than the front side thereof. Also the rear face of the part 8 is preferably in substantially the same plane as the rear face of the body 4 so that a smooth and relatively wide surface is provided as shown in Fig. 2.

There is what may be called a centrally-disposed projection 14 at the inner edge of the body 4. This is preferably curved as shown and in this way there are recesses 15 at opposite sides thereof which are adapted to receive the fingers, if desired, when throwing the shoe. This tends to make for more accurate guiding of the throw.

Furthermore, the projection 14, being curved, is adapted to act as a deflecting member when it strikes the stake. That is to say, if the device is pitched so that its part 14 strikes the stake, it will tend to be deflected to either side of the part 14 so that the arms 6 engage the stake rather than be propelled backwards so that arms 6 pass by opposite sides of the stake.

The forward ends of the arms 6 are formed so that their foremost edges 20 converge rearwardly and inwardly as shown. That is to say, the said ends are so shaped that in the event that in pitching the shoe, the forward end of one of its arms 6 were to strike the stake, it would serve more or less as a cam and cause the device to be deflected onto the stake.

The forward ends of the arms 6 are also provided with raised calk-like parts 16. These extend upwardly from the side of the device as does the part 8 and they have forward downwardly sloping faces 18 which also converge rearwardly and inwardly as shown.

Not only do these faces 18 co-operate with the edges 20 to deflect the device in the desired manner, but they are so arranged that they facilitate the device's sliding on the ground towards the stake if, as above stated, the device should happen to hit the ground before it reaches the stake.

One advantage of the device of this invention is that, as contrasted with prior art devices of this class which are likely to bound objectionably upon striking the ground, my new shoe is formed so that it tends to slide on its inclined surfaces 10, 12 and 18.

According to the preferred form of the invention, the inner edges of the forward parts of the side arms 6 are hook-shaped as at 22. These are adapted to engage the stake and in some cases prevent the device from falling out of the desired position.

The forward edges 20 of the arms are preferably inclined so that the angle α is approximately 80° . In this way the forward ends of the device are more or less pointed as contrasted with the blunt ends of ordinary playing shoes and the desired cam effect is attained.

While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

A game device of the class described comprising

ing in combination, a substantially U-shaped member having substantially flat upper and lower surfaces and including a semi-circular rear portion and arm portions extending forwardly from opposite ends of the semi-circle, the forward ends of said arm portions being formed to have adjacent substantially vertical edges which converge inwardly and rearwardly from the outer extremities of the forward ends towards said rear portion and said arm portions being provided with hooks on their inner sides which are disposed at the rear of the termination of said vertical edges, and calks provided on the upper surface of said forward ends of the arm portions adjacent said vertical edges, the upper faces of said calks being substantially flat and inclining upwardly away from the vertical edges and in diverging directions with the planes of said faces converging towards one another.
